DESIGN FOR AN ULTRAVIOLET STERILIZER

Robert A. Hrabak, Lakewood, Ohio, assignor to
The Art Metal Company, Cleveland, Ohio, a cor-
poration of Ohio

Application August 10, 1942, Serial No. 107,873

Term of patent 14 years

To all whom it may concern:

Be it known that I, Robert A. Hrabak, a citizen of the United States and a resident of Lakewood, in the county of Cuyahoga and State of Ohio, have invented a new, original, and ornamental Design for an Ultraviolet Sterilizer, of which the following is a specification, reference being had to the accompanying drawing, forming a part thereof.

In said drawing, Fig. 1 is a front elevational view of an ultraviolet sterilizer showing my de-

sign; Fig. 2 is a top plan view; Fig. 3 is a rear elevational view; Fig. 4 is an end elevational view; Fig. 5 is a cross-sectional view on the line 5—5 of Fig. 1; and Fig. 6 is a top plan view similar to Fig. 2 but with the ultraviolet lamp or tube omitted.

I claim:

The ornamental design for an ultraviolet sterilizer, substantially as shown.

ROBERT A. HRABAK.
